(57) **CLAIM**

The ornamental design for a portable electric screw driver, as shown and described.

DESCRIPTION

FIG. 1 is a front perspective view of the portable electric screw driver;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

1 Claim, 5 Drawing Sheets*FIG. 1*

FIG. 2

FIG. 3

*FIG. 4**FIG. 5**FIG. 6*

FIG. 7

UNITED STATES PATENT AND TRADEMARK OFFICE
CERTIFICATE OF CORRECTION

PATENT NO. : Des 440,850 S
DATED : April 24, 2001
INVENTOR(S) : Takashi Ozawa, et al.

Page 1 of 1

It is certified that error appears in the above-identified patent and that said Letters Patent is hereby corrected as shown below:

Title page.

Under Section “[30] Foreign Application Priority Data”, change “12-005085” to -- 2000-005085 --.

Signed and Sealed this

Thirtieth Day of October, 2001

Attest:

Nicholas P. Godici

Attesting Officer

NICHOLAS P. GODICI
Acting Director of the United States Patent and Trademark Office
